UNITED STATES PATENT OFFICE.

MICHAEL KITE, OF PRAIRIE TOWNSHIP, JACKSON COUNTY, MISSOURI.

SULKY-PLOW.

SPECIFICATION forming part of Letters Patent No. 269,427, dated December 19, 1882.

Application filed July 17, 1882. (No model.)

To all whom it may concern:

Be it known that I, MICHAEL KITE, of Prairie township, in the county of Jackson and State of Missouri, have invented a new and useful Improvement in Double-Hinge Couplings for Sulky-Plows, of which the following is a full, clear, and exact description.

Reference is to be had to the accompanying drawings, forming a part of this specification, in which similar letters of reference indicate corresponding parts in all the figures.

Figure 1 is a sectional side elevation of a part of a sulky-plow to which my improvement has been applied. Fig. 2 is perspective view of my improvement, shown as applied to a plow-beam and draw-bail. Fig. 3 is a front elevation of the same, the plow-beam being shown in cross-section.

The object of this invention is to improve the construction of the double-hinge couplings for which Letters Patent No. 251,895 were granted to me January 3, 1882, in such a manner as to give the plow better control over the sulky and prevent side draft upon the sulky-tongue.

The invention consists in a double-hinge coupling for sulky-plows, constructed with a clamp to hold the plow-beam, and connected by a bolt with a bracket and bent brace-bar hinged to the draw-bail, whereby the plow-beam will firmly control the sulky and prevent side draft, while having a free lateral and vertical movement, as will be hereinafter fully described.

A represents a wheel, B the arched axle, C the tongue, and D the draw-bail, of an ordinary plow-sulky.

E represents the beam, F the handles, G the standard, and H the mold-board, of an ordinary plow.

I is a U-shaped bar, which passes around the plow-beam E, and has a bolt, J, passed through its projecting ends at one side of the said beam. The bar I and bolt J form a clamp to receive and hold the plow-beam E, and are secured to the said plow-beam by one or more set-screws, K, which pass through the upright middle part of the bar I and rest against the said beam.

L is an upright bar, the lower end of which is bent outward at right angles, and has a hole formed through it to receive the lower end of the bolt J.

To the side bar, L, is secured, by the bolts M, N, a bar, O, the upper end of which is bent outward at right angles, and has a hole formed through it to receive the upper end of the bolt J. The clamp I, bolt J, and bars L O thus form a hinge and allow the plow-beam to have a free lateral play.

To the lower part of the bar L is secured, by the bolt N, the lower end of the bar P, which is bent outward, inclined outward and upward, and its upper end is bent upward, so as to be parallel with and at the same height as the upper end of the bar L.

Between the lower parts of the bars L P is interposed the end of a bar, R, which is secured in place by the bolt N. The bar R is bent at right angles, passes beneath the bars L I, and has a hole formed through it to receive the bolt J, by which it is secured in place. At the other side of the beam E the bar R is bent upward at right angles, so as to be parallel with the bar L, and the said bar is made of such a length that its upper end will be at the same height as the bars L P.

In the upper ends of the bars P L R are formed holes to receive the draw-bail D. The bars P L R and the draw-bail D thus form a hinge to give the plow-beam E a free vertical play.

The coupling is kept in place by one or more collars or clamps, Q, placed upon the bail D, between the bars P L or between the bars L R, or in both places, and secured in place by set-screws, clamping-screws, or other suitable means.

The coupling can be applied to and removed from the draw-bail D by taking out the bolts J N, which allow the bars P L R to be slipped over the angles of the said bail.

With this improvement the plow-beam will have a more direct draft upon the sulky, so as to avoid any side draft and prevent side pressure by the sulky-tongue.

If desired, the coupling can be made without the inclined bar P; but I prefer to use the said bar, as giving the plow-beam better control of the sulky.

I have shown and described my double-hinge coupling as swinging below the draw-bail; but with most plows it will be used above the bail, its position depending upon the construction of the sulky and of the plow to be connected.

with the sulky. Another advantage of this construction is, that it allows a square corner to be turned without raising the plow out of the ground.

5 Having thus described my invention, I claim as new and desire to secure by Letters Patent—

1. A double-hinge coupling for sulky-plows, constructed substantially as herein shown and described, and consisting of the plow-beam clamp I, the bracket O L P, the bent brace-bar R, and the bolt J, as set forth.

10 2. In a double-hinge coupling for sulky-plows, the combination, with a draw-bail, D, the plow-beam clamp I, the bars O L, and the bolt J, of the bent base-bar R, substantially as herein

15 shown and described, whereby the coupling is strengthened against lateral strain, as set forth.

3. In a double-hinge coupling for sulky-plows, the combination, with the draw-bail D, of the plow-beam clamp I, the brackets O L P, the bent brace-bar R, and the bolt J, the clamp turning horizontally on the bolt and the bracket and brace-bar turning vertically on the bail, whereby the plow-beam will firmly control the sulky and prevent side draft, while having a free lateral and vertical movement, as set forth.

MICHAEL KITE.
